(57) **CLAIM**

The ornamental design for an in-vitro fertilization embryo transfer cap, as shown and described.

DESCRIPTION

FIG. 1 is a perspective view of an in-vitro fertilization embryo transfer cap showing an embodiment of the design of the invention.

FIG. 2 is a front view thereof.

FIG. 3 is a rear view thereof.

FIG. 4 is a side view thereof, the opposite side being a mirror image thereof.

FIG. 5 is a top view thereof.

FIG. 6 is a bottom view thereof; and,

FIG. 7 is another perspective view thereof, in use.

The broken line showing of a structural feature, in this figure, FIG. 5 and FIG. 7, is included for the purpose of illustrating non-claimed subject and forms no part of the claimed design.

1 Claim, 4 Drawing Sheets

FIG. 1

FIG. 2

FIG. 3

FIG. 4

FIG. 5

FIG. 6
